2 SHEETS - SHEET 2.

UNITED STATES PATENT OFFICE.

CHARLES MINK, OF HOLGATE, OHIO.

MIXING-MACHINE.

1,181,153.

Specification of Letters Patent.

Patented May 2, 1916.

Application filed February 25, 1914. Serial No. 820,810.

To all whom it may concern:

Be it known that I, CHARLES MINK, a citizen of the United States, and a resident of Holgate, in the county of Henry and State of Ohio, have invented a certain new and useful Mixing-Machine; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to mixing machines. It has for its object to provide a means for making proportionate mixtures and regulating the amount of the elements which enter into resultant compositions.

20 My invention is particularly advantageous when used in mixing elements which combine in the formation of concrete. When used for that purpose, the cement, stone and sand are mixed together in proportions which differ according to the character for which the concrete is to be used. The proportions may be regulated by adjustable elements contained in the machine.

25 The invention may be contained in many constructions all of which come within the purview of the claim hereinafter appended. To show the practicability of constructions embodying my invention, I have selected one of such constructions as an example and 30 shall describe it hereinafter. The construction selected is illustrated in the accompanying drawings.

Figure 1 is a side view of a machine embodying the invention, part of the machine 35 being shown broken away and part in section in order to more clearly illustrate the elements of the machine. Fig. 2 is a view of a detail usable for cleaning one of the mixing troughs. Fig. 3 is a top view of the 40 machine shown in Fig. 1, a part being removed to show some of the mechanism.

In the figure, 1 is the frame or body of the machine which is supported on the front and rear wheels 2 in order that the machine 45 may be easily transferred from place to place. An engine 3 may be provided for driving the parts of the mechanism. The engine 3 is shown as supported centrally upon the frame 1. A double hopper 4, located on the frame 1, is provided with a 50 separating partition 5. The partition 5

may be made removable if desired. The lower end of the hopper 4 is closed by a 55 slideable bottom 6, supported at its ends in the channels 7. The bottom 6 is located in spaced relation with respect to the end walls 8 of the mouth of the hopper 4. The lower end of the partition 5 extends to a point in close proximity to the slideable bottom 6. As the bottom 6 shifts back and forth in the grooves 7, the material contained on one side of the partition 5 in the hopper 4, will fall through the space formed between the edge of the bottom and the lower edge of the end wall 8 located on that 65 side of the hopper. When the bottom 6 is shifted, the material contained in the opposite side of the partition will fall from the other chamber of the hopper through the space formed between the edges of the end 70 wall and the bottom located on that side. This will be on the side opposite the direction in which the bottom is shifted. The proportionate amounts of material that will pass through the space between the bottom 75 and the end walls of the hopper may be varied by means of a shutter or damper plate 9 secured to one end wall of the mouth of the hopper by means of bolts 10 located in slots formed in the plate 9. The 80 ratio of the material that will be allowed to pass out from the chambers of the hopper, may thus be varied according to the position of the lower edge of the plate 9 which may be adjusted with respect to the space formed 85 between the edge of the end wall of the mouth of the hopper and the edge of the movable bottom. The lower the plate 9 is positioned with respect to the lower edge of 90 the end wall of the mouth of the hopper, the less will be the amount of material that is allowed to pass out of the chamber located on that side of the partition.

A suitable means is provided for shifting the bottom 6 back and forth to permit the material to fall first from one chamber of the hopper and then from the other. I have provided a link or whip-rod 12 which is connected to the bottom by means of the bifurcated bracket or ears 13 at one end, and to the crank shaft 14 at the other end. The crank and its shaft 14 is rotated by means of the sprocket wheel 15 and chain 16 which is connected to the engine 3 through suitable driving mechanism. As the crank shaft 110 14 is rotated, the bottom 6 is slid back and forth in the channel 7. The link 12 may

be made rectangular in form as shown in Fig. 1, in order to permit the material to freely fall from the hopper 4 and prevent the material from striking the link as it falls from the hopper.

As material falls from first one edge of the bottom and then from the other edge, it descends to an apron 20 and to the trough 21. The apron 20 and the trough 21 may 10 be made of sheet metal suitably supported by the frame 1. The apron 20 guides the material that falls thereon to the trough 21. In the trough 21, the materials which fall from the compartments of the hopper 4, are 15 mixed by means of a mixing device such as the beater 25. It consists of a drum 26 having radially extending arms 27 which extend into and to near the bottom of the trough 21. The arms 27 are secured to the 20 drum 26 by bolts 28. The drum is rotated by the sprocket wheel 29 and chain 30. The arms 27 are located in spaced relation around the drum and along the drum, as 25 shown in Figs. 1 and 3. They operate to mix the materials in the trough 21 and at the same time work them from one edge of the trough 21 through and up over the other edge of the trough 21 as the drum 26 is rotated. The material then falls upon the 30 apron 35 and is directed thereby to the trough 36 toward which the apron 35 is inclined. The trough 36 is made of sheet iron and is suitably strengthened and supported by parts of the frame 1. A conveyer 37 is 35 located in the trough 36 and operated by the pulley wheel 39 and belt 40. The belt is driven by suitable driving mechanism. The conveyer 37 may be the ordinary screw 40 conveyer or it may be provided with plows 41 having faces so inclined with respect to the axis of the supporting shaft 42 as to work the material to the mouth 43 of the trough 36. The mouth 43 is located on one 45 side of the frame 1 and in position so that receptacles, such as pails or wheel barrows, may be placed beneath the mouth and the materials collected. The plows not only operate to convey the material to the mouth of the trough, but also operate to further 50 mix the materials directed into the trough.

In the operation of the device, the materials may be mixed dry in the trough 21 which will require but comparatively little power and then directed into the trough 36 to which a fluid may also be directed and the materials may be mixed wet therein. This is of particular advantage in making concrete mixtures. Water may be directed through the pipe 45 and valve 46 into the trough 36 and the mixture directed into the trough 36 may be saturated to the degree required according to the purposes for which the resultant mixture is to be used.

The mechanism for driving the parts of the mixing machine, receives its power from

the engine 3 which drives the pulley 50 and the fly-wheel 52 by means of the belt 51. The pulley 50 and the fly-wheel 52 are suitably mounted on the shaft 53 to which is also keyed the spur gear 54. The spur gear 54 meshes with the gear wheel 55 which is keyed to the shaft 56. The sprocket gear 58 is also keyed to the shaft 56. The pulley wheel 57 drives the pulley 39 to which it is connected by means of the belt 40. The sprocket gear 58 drives the sprocket gear 29 to which it is connected, by the sprocket chain 30. This causes the plows 41 secured to the shaft 42 to rotate and convey the material through the trough 36 to the mouth 43 and also mixes the mixture lifted from the trough 21 into the trough 36 with the water which is directed through the pipe 45. This also rotates the drum 26 which mixes the dry mixture coming from the hopper 24 and works the material from one side of the trough 29 to the other side of the trough and lifts it onto the apron 35 from whence it falls to the trough 36. The gear 59 is keyed to the shaft of the drum 26 and drives the sprocket wheel 15 through the chain 16. The sprocket wheel 15 being keyed to the crank shaft 14, it causes the bottom 6 to slide back and forth permitting the material to fall first from one chamber 95 of the hopper 4 and then from the other chamber in regular amounts and in amounts which may be varied in proportion according to the position of the plate 9 relative to the lower edge of the end wall of the mouth 100 of the hopper on which it is located.

If desired, the trough 21 may be entirely cleared of its contents by means of the angular plate 60 shown in Fig. 2. One of the sides of the plate 60 is provided with openings 61. The angular plate 60 may be placed on the drum, the radial arms 27 extending through the holes 61. The drum 26 may then be rotated whereupon the rods 27 located behind one of the sides of the plates 60 will push the plate 60 before it and clear the trough 21 from the material contained therein. The trough 21 may thus be scraped clean by the plate 60.

The construction selected and described 115 may be greatly varied in the arrangement and construction of its parts and in the substitution of the elements having equivalent functions and such modifications may still contain the invention which is described in 120 the claim in the language of the elements shown.

What I claim as new and desire to secure by Letters Patent is as follows:

In a mixer, a drum having slender pins 125 attached thereto in spaced relation with respect to each other, a trough extending substantially semicircularly around the under side of the drum and so that the ends of the fingers extend to near the bottom of the 130

trough, an apron for feeding the material to one side of the drum and one edge of the trough, means for rotating the drum for mixing the material dry and conveying it
5 only transverse across the trough at right angles to the axis of the drum and over the edge of the trough opposite to that over which the materials are fed, a second trough extending parallel with the first-named
10 trough for receiving the material therefrom, and a pipe for directing water into the

second-named trough and a conveyer in said second trough for both mixing and conveying the material transversely to the conveyance in the first-named trough.

In testimony whereof, I have hereunto signed my name to this specification in the presence of two subscribing witnesses.

CHARLES MINK.
